UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

JOINT FOR ARTICLES OF CERAMIC AND SIMILAR MATERIALS AND METHOD OF PRODUCING SAME.

Original application filed November 17, 1919, Serial No. 338,534. Divided and this application filed March 31, 1922. Serial No. 548,331.

To all whom it may concern:

Be it known that I, ARTHUR O. AUSTIN, a citizen of the United States, residing at Barberton, county of Summit, and State of Ohio, have invented certain new and useful Improvements in Joints for Articles of Ceramic and Similar Materials and Methods of Producing Same, of which the following is a specification.

10 This invention has for its object the provision of joints or connections of the character named which shall be of improved construction and operation and the provision of an improved method of producing such joints.

The invention is exemplified in the combination and arrangement of parts shown in the accompanying drawings and described in the following specification and 20 in the steps of the process illustrated in the drawings and described in the specification. The invention is more particularly pointed out in the appended claims.

The present application is a division of 25 application, Serial No. 338,534, filed November 17, 1919.

In the drawings—

Fig. 1 is a section of a portion of an insulator illustrating one step in the process of forming the joint comprised in the present invention;

Fig. 2 is a similar view showing a different step in the process;

Figs. 3 and 4 are similar to Figs. 1 and 2 illustrating the application of the process to a different form of insulator;

Fig. 5 is a section of an insulator illustrating the application of the process in a slightly different manner;

Fig. 6 is a section of a portion of an insulator showing a different modification of the invention; and

Figs. 7 and 8 show other forms of the invention.

Broadly described, the invention comprises the joining of two parts composed of ceramic or similar material to one another by fusion at a plurality of limited points of contact.

The invention also contemplates the regulation of the closeness of the fit between

the parts by proportioning the relative shrinkage or expansion of the parts during firing.

The invention is especially applicable to 55 articles made of ceramic material, such as porcelain and vitreous insulators, tile, brick and other articles of like nature. In joining such articles together it is frequently desired to provide an elastic joint to prevent 60 injury due to unequal expansion and contraction and also to properly distribute forces transmitted from one part to another. Where articles, such as insulators for instance, have had their parts connected together by glazing material which 65 melts in firing and fills the space between the parts, great trouble has been experienced from cracking or bursting of the parts in all but the very small insulators. This has 70 prevented commercial success of glaze filled insulators, and other methods of joining parts have had to be resorted to.

In the present invention, a glaze joint 75 having an open mechanical structure is produced, which affords elasticity in the joint and overcomes the difficulties previously experienced. Results sought may be secured in a large variety of ways, some of which are illustrated and described herein, but it 80 is understood that the invention is not limited to the specific forms shown and described.

In the process of forming the joint, it is sometimes desirable to cause the connected 85 surfaces to approach one another more closely during the firing process.

Figs. 1 and 2 illustrate two stages in the formation of such a joint. In these figures an internal part 1 is provided with a corrugated surface 2 which fits into an opening in an outer part 3 having an interior corrugated surface 4. Before the parts are fired the inner part 1 is smaller than its surrounding part 3 so that the corrugations 95 of the two will pass one another to permit the parts to be assembled, as shown in Fig. 1. The outer part is made of material which has a greater shrinkage in firing than the inner part so that after the two parts 100 have been fired they will be brought closer together, as illustrated in Fig. 2. The dif-

ference in the amount of contraction of the two parts may be regulated by the composition of the clay of which the parts are made in a manner well known to those skilled in the art, or the inner part may be partially fired prior to assembly, so that it has already partially or totally shrunk when the two parts are placed together; this will cause a greater shrinkage of the outer part than the inner part in firing, and will produce the same result as where the outer part is made of material having a greater shrinkage than the inner part.

Figs. 3 and 4 illustrate similar steps to those described in connection with Figs. 1 and 2, but in this case the inner part 1 instead of being provided with corrugations 2 is threaded as shown at 5, the external threads on the part 1 being arranged to mesh with internal threads 6 on the part 3. With this arrangement it is not necessary for the points of the threads to pass one another in assembling the parts, but the two parts can be threaded together by a relative rotation. The joint will be loose, however, until the parts are fired, after which they will be in close contact, as illustrated in Fig. 4.

In Fig. 5 an internal member 8 fits into a cap 9 which is provided with projections 10 on its inner surface. A supplemental cap 11 is placed over the external member 9, and the space between the parts 9 and 11 may be packed with a loose material, such as quartz sand to prevent the parts 9 and 11 from being fused together in firing and to transmit pressure from the part 11 to the part 9. The part 11 is made of material which has a relatively high shrinkage in firing so that it will exert pressure on the part 9 and cause the projection 11 to be pressed closely into contact with the surface of the inner member 8. Before the parts are fired, one or the other, or both of the adjacent surfaces of the members 8 and 9 is covered with a glaze, which, during the firing operation will fuse the contacting points of the projections 10 to the outer surface of the interior member 8. This will provide a joint between the members 8 and 9 which is of open mechanical structure and which will afford sufficient resiliency between the two parts to overcome dangerous stresses which might be set up by unusual contraction or expansion if solid glaze were used for connecting the parts. The fact that the outer member is pressed into engagement with the inner one during the firing by the contraction of the cap 10 insures a union of the projections 10 with the member 8 and prevents any flaring of the external member away from the inner part. This method of contraction permits the use of a very small quantity of glaze, as it is unnecessary to provide an excess of glaze material to take up inequalities. All

the glaze necessary is an exceedingly thin coat on the surface, so that any difference in the coefficient of expansion of the glaze will have little or no effect on the adjacent body portions.

In Fig. 6 an internal member 12 is provided with projections 13 which may be formed by ribbing or knurling the surface of the internal member, or may be produced in a variety of ways. An external part 14 is fitted over the part 13 and may be made of material which will have a greater shrinkage in firing than part 12, so that the projections 13 will be pressed firmly into contact with the inner surface of the member 14 during firing. Instead of using material that will shrink differently, the parts may be caused to bear closely on one another in firing by shaping the parts so that the weight of one will tend to bring it closer to the other. This will be secured if the contacting surfaces are tapered and they will slide together during the firing operation. Sufficient glaze is provided between the two surfaces, either by glazing one or the other, or both, of the surfaces, so that when the parts are fired the projections 13 on the member 12 will be fused to the inner surface of the member 14 to form a resilient fused glazed joint.

Figs. 7 and 8 show internal members 15 and external members 16 which are caused to come into contact during firing in a manner similar to that described in connection with Fig. 6. In Fig. 7 the external member 16 is provided with circular ribs 17 which are pressed into the material in the member 15 during the firing process and fused to the member in a manner similar to that described. In Fig. 8 the projections 18 instead of being circular ribs, as shown in Fig. 7, are in the form of threads, so that the two parts may be screwed together, prior to firing, if desired. The parts may be so proportioned, however, that they will go together readily before firing and the outer part will contract upon the inner part to cause the threaded projections 18 to imbed themselves slightly in the inner member in a manner similar to that described in connection with Fig. 7. If the pieces are made to cause the projections on one to be imbedded sufficiently into the other to give mechanical strength, no glaze is necessary. The ribs or irregular surface has the advantage that it will imbed while the material is soft during the firing process and form an interlock. The smaller section of the ribs or irregular projections yield and are not so likely to cause damage to the outer part during the contracting period. The two surfaces may have any degree of contact by applying the glaze or fusing material in spots on the surface which only partially cover same.

- Where it is desirable to form a conducting surface in the joint for the distribution of electrostatic stress, this can be done by pouring a plating or metallizing solution into the porous joint, such as a silvering solution, or by introducing into the joint a composition which will remain or become conducting during the burning or firing of the parts.
- 10 Where it is desirable to prevent a discharge in the spaces and it is not desirable to use a conducting material, the open space in the joint may be filled with an insulating material, such as wax, paraffine, or oil, or 15 asphaltum.

I claim:—

1. In combination, a plurality of ceramic bodies having connection with one another at a plurality of points of limited extent, 20 said bodies being fused to one another at their points of connection to provide a yielding joint.
  2. In combination, a pair of ceramic bodies having adjacent surfaces, projections 25 on one of said surfaces having limited points of contact with the other thereof, said projections being fused to said last-mentioned surface at said limited points of contact, to form a resilient joint between said bodies.
  - 30 3. The process of uniting two ceramic bodies which have unequal shrinkage when firing, comprising the steps of assembling the bodies, introducing glazing material between the bodies and firing the bodies to cause one to shrink upon the other and to cause them to be fused together by said glazing material.
  4. In combination, a pair of vitreous bodies having adjacent surfaces, projections 40 on one of said surfaces having limited points of contact with the other thereof, said projections being fused to said last-mentioned surface at said limited points of contact to form a joint of limited amount 45 of material between said bodies.
  5. In combination, a pair of vitreous bodies, one of which has a part extending into an opening in another, said bodies being composed of material that will shrink 50 unevenly in firing to cause adjacent surfaces thereof to approach one another, and bodies interposed between said surfaces and having portions contacting with said surfaces and impressed therein by the shrinking of 55 said parts in firing.
  6. In combination, a plurality of ceramic bodies having connections with one another at a plurality of points of limited extent, said bodies being fused to one another at 60 their points of connection to provide a yielding joint, and conducting material in said joint.
  7. In combination, a pair of ceramic bodies having adjacent surfaces, projections
- on one of said surfaces having limited points of contact with the other thereof, said projections being fused to said last-mentioned surface at said limited points of contact to form a resilient joint between said bodies, and a coating of conducting material on one or both of said surfaces.
8. In combination, a pair of vitreous bodies having adjacent surfaces, projections on one of said surfaces having limited points of contact with the other thereof, said projections being fused to said last-mentioned surface at said limited points of contact to form a resilient joint between said bodies, and means for metallizing said joint.
9. An insulator having a pair of vitreous bodies one of which has a part extending into an opening in the other, said bodies being composed of material that will shrink unevenly in firing to cause adjacent surfaces thereof to approach one another, and means on one body interlocking with means on the other body to prevent the separation of the parts after firing.
10. An insulator comprising two parts having adjacent surfaces provided with complementary projections and depressions, one of said parts being positioned within the other and the outer part being composed of material having a greater shrinkage in firing than the inner part so that the projections and depressions will form an interlock for said parts after said parts have been fired.
11. An insulator comprising two parts composed of vitreous material and providing adjacent surfaces with interfitting formations thereon, said parts having different shrinkage when fired to cause said surfaces to approach one another and to bring said formations into interlocking relation to hold said parts together.
12. An insulator comprising two parts formed of vitreous material, one of said parts extending into the other, the adjacent surfaces of said parts being provided with interfitting formations, the material of the outer part having a greater shrinkage in firing so that said part may be moved into position on the inner part prior to firing but shrink into place during firing to cause said formations to lock said parts together.
13. An insulator comprising two parts having adjacent surfaces, one of said parts being positioned within the other and the outer part being composed of material having a greater shrinkage in firing than the inner part, and means interposed between said surfaces and extending into indentations therein for holding said parts together.
- In testimony whereof I have signed my name to this specification on this 27th day of March, A. D. 1922.
- ARTHUR O. AUSTIN.
